UNITED STATES PATENT OFFICE

THEODORE J. GLASS, OF INGLEWOOD, CALIFORNIA, ASSIGNOR TO JOSEPH M. FULLER, OF INGLEWOOD, CALIFORNIA

DESIGN FOR A CIGARETTE DISPENSER

Application filed August 27, 1930. Serial No. 36,789. Term of patent 14 years.

To all whom it may concern:

Be it known that I, THEODORE J. GLASS, a citizen of the United States, residing at Inglewood, in the county of Los Angeles and State of California, have invented a certain new, original, and ornamental Design for a Cigarette Dispenser, of which the following is a specification, reference being had to the accompanying drawing, forming a part thereof, in which—

I claim:

The ornamental design for a cigarette dispenser, substantially as shown.

In testimony whereof, I have hereunto set my hand at Inglewood, California, this 15th day of August, 1930.

THEODORE J. GLASS.
